COMBINED PADDLE AND CATCHING TOY

Eugene R. Caporale, 225 Stephen St.,
North Bellmore, N.Y.

Filed Mar. 20, 1964, Ser. No. 79,103

Term of patent 14 years

(Cl. D34—5)

FIG. 1

FIG. 2

FIG. 3

FIG. 5

FIG. 1 is a top plan view of a combined paddle and catching toy showing my new design,

FIG. 2 is a side view,

FIG. 3 is an end view looking at the lefthand side of FIG. 2,

FIG. 4 is a bottom view, and

FIG. 5 is a cross-sectional view of FIG. 1 taken along lines 5—5.

I claim:

The ornamental design for a combined paddle and catching toy, substantially as shown.
